UNITED STATES PATENT OFFICE

140,570

DESIGN FOR A SWITCH CASING OR SIMILAR ARTICLE

Henry G. Leupold, Cambridge, Mass., assignor to
United Electric Controls Company, South
Boston, Mass., a corporation of Massachusetts

Application October 11, 1944, Serial No. 115,714

Term of patent 7 years

(Cl. D26—13)

To all whom it may concern:

Be it known that I, Henry G. Leupold, a citizen of the United States of America, residing at Cambridge, in the county of Middlesex and Commonwealth of Massachusetts, have invented a new, original, and ornamental Design for a Switch Casing or Similar Article, of which the following is a specification, reference being had to the accompanying drawing forming a part thereof.

Fig. 1 is a side elevation of a switch casing embodying my new design;

Fig. 2 is an end elevation of the switch casing shown in Fig. 1;

Fig. 3 is a bottom view of the switch casing; and

Fig. 4 is a plan view of the switch casing.

I claim:

The ornamental design for a switch casing or similar article, substantially as shown.

HENRY G. LEUPOLD.
